UNITED STATES PATENT OFFICE

GEORGE McBRIDE, OF BELFAST, IRELAND

MAIL BAG

Application filed July 27, 1929, Serial No. 381,580, and in Great Britain November 27, 1928.

This invention relates to devices for attachment to doors or other places for the reception of mail, its object being to provide a simple and inexpensive device for such purpose. A further object is to provide such a device in the form of a fabric bag formed from a piece of fabric so shaped and foldable that the bag can lie flat against the door or other place, and when opened for extraction 10 of mail, gives easy access to the interior.

According to this invention I provide a bag for attachment to doors or other places for the reception of mail, such bag being formed from a substantially rectangular piece of 15 fabric having two adjacent corners cut off, by folding over and joining together the two side portions having the cut-off corners, fitting in a frame at the top or mouth of the bag (i. e., where the cut-away corners are) 20 in order to keep the same opened out, and closing the bottom of the device.

The aforesaid frame of the bag is preferably hinged to the article to which the bag is attached so that it can be moved into a position to enable the mail to be easily removed 25 therefrom.

The invention will now be described with reference to the accompanying drawings whereon an example is given of a door letter 30 opening with a preferred construction of the bag applied thereto.

Fig. 1 is an elevation showing the letter bag in position at the back of a door behind the letter opening therein, the bag being 35 shown in position for receiving letters.

Fig. 2 is a sectional elevation on the line XX Fig. 1.

Fig. 3 is a plan view showing the bag with the mouth moved down to the horizontal position to give access to the bag.

Fig. 4 shows how the material, from which the bag is made, is shaped and how it is folded over for attachment to the rigid frame.

Fig. 5 is an elevation of the top of the bag, 45 corresponding to Fig. 1, showing the mouth of the bag attached to a plate which can be readily secured by screws to the back of a door behind the letter opening therein.

Fig. 6 is an elevation of the letter bag 50 shown in Fig. 1, but looking in the opposite

direction; it shows the side edges of the formed and folded bag in relation to the edges of the piece of material, and also shows the folds in the mouth of the bag at the rigid frame.

Referring to the drawings:—

The flexible bag of fabric 1 is made from a piece of material shaped as in Fig. 4 folded over along the lines 7, 8 and joined along the line 9. It is important that the top corners of the otherwise rectangular material should be cut off, as indicated at 1^a, to ensure that the material behind the mouth of the bag, in the position shown at Fig. 1, will lie flat against the letter opening 2 in the door, and the cut away corners may with advantage be slightly curved. The mouth of the bag is shown secured to a rigid frame 3 of rectangular shape secured to a hinge 4; this frame is secured to the fabric in the position shown in dotted lines in Fig. 4. The edges 1^a of the fabric 1 are stitched over the sides of the wire frame at 3^a (Fig. 6) while the two lateral edges of the fabric are stitched together at 9^a, corresponding to the line 9, Fig. 4. Owing to the shape of the piece of fabric shown in Fig. 4, when the bag is flattened out, folds substantially at 10 and 11 (Fig. 6) appear at either side adjacent to the frame, the fold 11 being underneath the fold 12. When the bag is opened as at Fig. 3, for extraction of letters or the like, the folds 10 and 11 open out and enable free access to be had to the bag.

In the example shown the hinge 4 has a dented portion 4^a and there is a corresponding dent in the wire frame 3. These interengaging indentations effectively locate the position of the wire frame 3 and prevent it from sliding through the hinge, avoiding the use of washers, or other means to hold the frame in position in the hinge. If desired, more than one hinge may be used, but a single hinge as shown is adopted for cheapness.

The rectangular mouth frame 3 to which the top of the bag is attached can be swung about the hinge 4 and when required moved to the position shown in plan at Fig. 3. In this position easy access is given to the bag from behind the door. A catch 5 is shown

for holding the mouth of the bag against the back of the door as shown at Figs. 1 and 2. Instead of the catch shown, a more elaborate form of clip could be used.

5. If desired, the hinge 4 may be attached to a plate 6 which can be readily secured by screws 6^a, or equivalent, to the back of the door.

10 The invention has been described throughout as applied to a door, but it can be readily applied to letter openings in windows, partitions and elsewhere. The device can also obviously be used for the reception of circulars, papers, and other mail matter.

15 The invention is simple and cheap. It can be sold readily through the post as the bag will fold up flat for mailing purposes.

I claim:—

20 1. A bag for the reception of mail matter comprising in combination; a substantially rectangular piece of fabric having two adjacent corners cut off, the two side portions (of the piece of fabric) having the cut off corners, being folded over and joined together; a 25 frame member attached to said piece of fabric at the top thereof (that is, where the cut away corners are) forming a mouth; and a closure on the bottom of the bag.

30 2. A bag for the reception of mail matter comprising in combination; a substantially rectangular piece of fabric having two adjacent corners cut off, the two side portions (of the piece of fabric) having the cut off corners being folded over and joined together; a frame member attached to said piece of fabric at the top thereof (that is, where the cut away corners are) forming a mouth, a closure on the bottom of the bag; a support for the bag; and means hingeably attaching 35 said bag by its frame, to said support.

40 3. A bag for the reception of mail matter comprising in combination; a substantially rectangular piece of fabric having two adjacent corners cut off, the two side portions (of the piece of fabric) having the cut off corners being folded over and joined together; a frame member attached to said piece of fabric at the top thereof (that is, where the cut away corners are) forming a mouth, a closure on the bottom of the bag; a support for the bag; at least one hinge, each attached to said support and hingeably supporting said bag by its frame; and corresponding indentations in said frame member and in each hinge, said indentations being adapted to engage with each other and grip said bag either in a position preventing access, or in a position giving access, to the interior thereof.

45 4. A bag for the reception of mail matter comprising in combination; a substantially rectangular piece of fabric having two adjacent corners cut off, the two side portions (of the piece of fabric) having the cut off corners being folded over and joined together; a

substantially rectangular frame member to which the top edges of said piece of fabric are stitched, forming a mouth; and a closure on the bottom of the bag.

5. A bag for the reception of mail matter comprising in combination; a substantially rectangular piece of fabric having two adjacent corners cut off, the two side portions (of the piece of fabric) having the cut off corners being folded over and joined together; a substantially rectangular frame member to which the top edges of said piece of fabric are stitched (that is, where the cut away corners are), forming a mouth; a closure on the bottom of the bag; a support for the bag; at least one hinge, each attached to said support and hingeably supporting said bag by its frame; and corresponding indentations in said frame member and in each hinge, said indentations being adapted to engage with each other and grip said bag either in a position preventing access, or in a position giving access, to the interior thereof.

In testimony whereof I affix my signature.

GEORGE McBRIDE.
